CLAIM

The ornamental design for a curved cornhole crossbar, as shown and described.

DESCRIPTION

FIG. 1 is a perspective view of a curved cornhole crossbar showing the claimed design.

FIG. 2 is a right-side view thereof, the left-side view being a mirror image thereof.

FIG. 3 is a top view thereof.

FIG. 4 is a bottom view thereof.

FIG. 5 is a rear view thereof; and,

FIG. 6 is a front view thereof.

Broken lines in the figures show portions of the curved cornhole crossbar that form no part of the claimed design.
